COMBINED LINT REMOVER AND FABRIC COMBER

Frank S. Thomas, Jr., 1715 Camden Ave.,
Los Angeles, Calif.

Filed Oct. 20, 1964, Ser. No. 82,257

Term of patent 14 years

(Cl. D9—2)

The drawing is shaded to show contrast.

I claim:

The ornamental design for a combined lint remover and fabric comber, as shown and described.
